RAILWAY SIGNALING SYSTEM

Ralph R. Kemmerer, Swissvale, Pa., assignor to
The Union Switch & Signal Company, Swiss-
vale, Pa., a corporation of Pennsylvania

Application July 30, 1942, Serial No. 452,893

14 Claims. (Cl. 246—38)

My invention relates to railway signaling systems of the type employing wayside signals of the searchlight type.

In some systems where more than two proceed indications are desired the wayside signals employ upper and lower units each comprising a searchlight signal unit. These signal units cooperate to provide the various indications. However, only certain combinations of aspects of the two signal units are authorized. It is desired to check the response of the signals to determine if they are displaying the proper aspects, and to govern the supply of signal control energy to the adjacent section in the rear so that if a signal is displaying an unauthorized indication the adjacent signal in the rear will be prevented from displaying its least restrictive indication.

An object of my invention is to provide an improved railway signaling system of the type employing wayside signals having two searchlight signal units, the system being arranged so that the signals are checked to determine if they are displaying the proper aspects.

Another object of the invention is to provide a system of the type described and having means governed by the signals and controlling the supply of energy to the adjacent section in the rear.

A further object of the invention is to provide a signaling system of the type described in which one of the signal units controls the supply of energy to the other signal unit to thereby prevent the display of an unauthorized combination of aspects by the two signal units.

Another object of the invention is to provide a system of the type described and incorporating means to delay certain types of changes in the signals to thereby prevent momentary display of incorrect or unnecessarily restrictive aspects by the signals.

Other objects of the invention and features of novelty will be apparent from the following description taken in connection with the accompanying drawings.

I shall describe four forms of apparatus embodying my invention and shall then point out the novel features thereof in claims.

In practicing my invention I provide repeater relays to detect response of the signal units to changes in the signal control relays and I employ these repeater relays to control the supply of energy to the adjacent section in the rear. In some modifications these repeater relays directly control the supply of energy to the section in the rear, and in other modifications the repeater relays control the supply of energy to the section

in the rear through a checking relay which checks correspondence between the signal control and signal repeater relays. In addition, in some modifications the signal repeater relays for the upper signal unit control the supply of energy to the winding of the lower signal unit, while in each of the modifications the lightout relay for the upper unit of a signal controls the polarity of the energy supplied to the lower unit of the signal so that energy effective to cause the lower unit of the signal to display a green light cannot be supplied to the winding of this unit if the lamp of the upper unit of the signal is burned out. In some modifications of the invention the green repeater relay for each signal unit is slow in releasing and when picked up establishes a circuit to supply energy to the winding of the associated signal unit to delay changes in this signal unit until the signal control relays respond to changes in traffic conditions and thus prevent the momentary display of unnecessarily restrictive indications.

In the drawings

Figs. 1 and 3 are diagrams of systems embodying my invention and having wayside signals arranged to provide four aspects, and

Figs. 2 and 4 are diagrams of signaling systems also embodying my invention and having wayside signals arranged to provide five aspects.

Similar reference characters refer to similar parts in each of the several views.

Referring to Fig. 1 of the drawings there is shown therein a stretch of railroad track having track rails 1 and 2 over which traffic normally moves in the direction indicated by the arrow, that is, from left to right. The rails of the track stretch are separated by insulated joints 3 into the customary successive track sections, and the rails of each of these sections form a part of a track circuit of the usual character.

The system shown employs alternating current energy in the track circuits. This energy may be derived from any suitable source and may be distributed throughout the track stretch by a transmission line, not shown. In the drawings the terminals of the power supply source are designated BX and CX.

In the diagram forming Fig. 1 of the drawings one complete track section, designated 12T, and parts of two adjoining sections 11T and 13T, are shown. Each of these sections has located at the entrance end thereof a signal designated S with an appropriate prefix, for governing traffic in the track stretch. Each of these signals has an upper unit SU, and a lower unit SL, each com-

prising a familiar searchlight signal unit. Each of these signals is provided with a mechanism capable of selectively projecting a plurality of beams of light of different colors from a single light source. The construction of the signal units is not a part of this invention and these units may be of any well known construction. A signal unit of the type which I may employ is shown in Letters Patent of the United States No. 1,864,224, granted June 21, 1932, to Wesley B. Wells.

The signaling system shown in Fig. 1 is of the four indication variety and makes use of track circuit energy coded at three different frequencies. This coded energy is provided by code transmitters CT which interrupt the supply circuits for the associated track transformers a definite number of times a minute according to traffic or other conditions ahead. In the illustrative form shown, each code transmitter CT is provided with three circuit making and breaking contacts 75, 120 and 180 which are continuously actuated by a motor or other suitable mechanism at three different speeds. For purposes of illustration it will be assumed that these speeds are such as to provide 75, 120 and 180 energy pulses per minute which are separated by periods of equal duration in which no energy is supplied.

Each of the track sections includes a code following track relay designated TR together with an appropriate prefix. The track relay is located at the entrance end of the track section and may be of any suitable type. As shown, the track relay 12TR is of the direct current type and is connected to the track rails through a suitable rectifier 12R. The track relay 12TR has associated therewith a decoding transformer 12DT, signal control relays 12H, 12J and 12K, signal repeater relays 12UG, 12UY and 12LG, and a lightout relay 12ULO.

The relays 12J and 12K are energized from the decoding transformer 12DT through resonant rectifier units 180DU and 120DU, respectively. Each of these units includes an inductance and a capacitance which are arranged and proportioned so that when the frequency of the current supplied thereto is that present when the track relay is responding to energy of a particular code frequency sufficient energy is supplied through the unit to pick up the associated relay. Each unit is also arranged so that when energy of a substantially different frequency is supplied thereto insufficient energy is supplied to the associated relay to pick up its contacts. Each of these units includes a rectifier which rectifies the energy supplied through the unit.

The elements of the unit 120DU are proportioned so that the relay 12K is picked up when the track relay is responding to energy of 120 code frequency, while the elements of the unit 180DU are proportioned so that the relay 12J is picked up when the track relay is responding to energy of 180 code frequency.

Each of the signals has associated therewith a source of direct current, such as a storage battery, not shown, the terminals of which are designated B and C.

The equipment is shown in the condition which it assumes when the track stretch is vacant. At this time, energy of 180 code frequency is supplied to the track transformer 12TT by the equipment associated with section 13T. It will be understood that this equipment is similar to that which supplies energy to the track transformer 11TT for section 11T. This energy feeds through

5 the rectifier 12R to track relay 12TR and produces code following operation of this relay with the result that the two portions of the decoding transformer primary winding are alternately energized and energy is induced in the transformer secondary windings.

Energy from one of these windings is rectified by a contact of the track relay and is supplied to relay 12H, while energy from the other transformer secondary winding is supplied through resonant rectifier unit 180DU to relay 12J.

As the relays 12H and 12J are picked up, energy of normal polarity is supplied to the winding of signal 12SU over the circuit which is traced from terminal B through front contact 20 of relay 12H, front contact 21 of relay 12J, winding of the signal, front contact 22 of relay 12J, and front contact 23 of relay 12H to terminal C. Accordingly, the signal mechanism conditions the signal to provide its green indication, while the contact G of the signal is closed so that energy is supplied to the relay 12UG and its contacts are picked up so that its contact 25 interrupts the circuit of the winding of signal 12SL. At this time, as signal 12SU is displaying its green indication, relay 12UY is released and its contacts 27 and 28 additionally interrupt the circuit of the winding of signal 12SL. Accordingly, the signal 12SL displays its red indication so the signal 12S displays its clear indication consisting of a green light over a red light.

As relays 12H and 12UG are picked up, energy of 180 code frequency is supplied to track transformer 11TT over the circuit which is traced from terminal BX through contact 180 of code transmitter 12CT, front contact 30 of relay 12UG, front contact 31 of relay 12H, and primary winding of transformer 11TT to terminal CX. Accordingly, energy of 180 code frequency is supplied to the rails of section 11T and the signal for this section displays its clear indication.

The signal lamps are normally lighted at all times, while the circuit of the lamp of the upper signal includes in series therewith the light-out relay 12ULO so that this relay is picked up as long as the lamp filament is intact.

When a train moving in the normal direction of traffic enters section 12T, the track relay 12TR is shunted and relays 12H and 12J release. On release of relay 12H its contacts 20 and 23 interrupt the supply of energy to the winding of signal 12SU so this signal displays its red indication, while when contacts 20 and 23 of relay 12H are released energy cannot be supplied to signal 12SL so it continues to display its red indication. Accordingly, signal 12S displays its stop indication consisting of a red light over a red light.

When the signal 12SU displays its red indication its contact G interrupts the circuit of the relay 12UG, while at this time the circuit of this relay is additionally interrupted by contact 33 of relay 12J.

On release of relay 12H its contact 31 interrupts the supply of energy of 180 code frequency to the transformer 11TT and establishes the circuit for supplying energy of 75 code frequency thereto.

When the train advances into section 13T the signal for that section is caused to display its stop indication, while energy of 75 code frequency is supplied to transformer 12TT. When the train vacates section 12T, this 75 code energy feeds to relay 12TR and the relay causes energy to be supplied through the decoding transformer

12DT to the relay 12H so that its contacts are picked up. The rate of operation of the track relay 12TR on 75 code is such that energy is not supplied through the units 180DU and 120DU and the relays 12J and 12K remain released.

When relay 12H picks up, its contacts 20 and 23 establish a circuit to supply energy of reverse polarity to the winding of signal 12SU. This circuit is traced from terminal B through front contact 20 of relay 12H, back contact 34 of relay 12UG, back contact 22 of relay 12J, winding of signal 12SU, back contact 21 of relay 12J, back contact 35 of relay 12UG, and front contact 23 of relay 12H to terminal C. This energy causes the signal mechanism to condition the signal to display its yellow indication, while the front contact Y of the signal is closed to establish the circuit to supply energy to the relay 12UY and contacts 27 and 28 of this relay are picked up. However, at this time the contacts of relays 12LG and 12K are released so the circuit of the winding of signal 12SL is interrupted and this signal continues to display its red indication. Accordingly, the signal 12S now displays its approach indication consisting of a yellow light over a red light.

On picking up of the contacts of relay 12H its contact 31 interrupts the supply of energy of 75 code frequency to section 11T and establishes the circuit to supply energy of 120 code frequency thereto. This circuit is completed on picking up of relay 12UY and is traced from terminal BX through contact 120 of code transmitter 12CT, front contact 37 of relay 12UY, back contact 38 of relay 12LG, back contact 30 of relay 12UG, front contact 31 of relay 12H, and primary winding of transformer 11TT to terminal CX. It will be seen that the circuit for supplying energy of 120 code frequency to section 11T includes contacts of the signal repeater relays 12LG and 12UG so that this circuit will not be established if the lower signal 12SL should improperly display its green indication or the upper signal 12SU should improperly display its green indication.

When the train advances far enough to vacate section 13T the signal for that section is conditioned to display its approach indication, while energy of 120 code frequency is supplied to the rails of section 12T. This energy feeds to relay 12TR and operates it at a rate such that energy is supplied through the unit 120DU and picks up the relay 12K so that its contacts 40 and 41 establish the circuit to supply energy of normal polarity to the winding of signal 12SL. The circuit for supplying energy to signal 12SL is traced from terminal B through front contact 20 of relay 12H, back contact 25 of relay 12UG, front contact 42 of relay 12ULO, front contact 40 of relay 12K, front contact 27 of relay 12UY, winding of signal 12SL, front contact 28 of relay 12UY, front contact 41 of relay 12K, front contact 43 of relay 12ULO, and front contact 23 of relay 12H to terminal C. The energy of normal polarity supplied to signal 12SL causes the signal mechanism to condition the signal to provide its green indication so that the signal 12S displays its approach medium indication consisting of a yellow light over a green light.

It will be seen that the circuit for supplying energy of normal polarity to the winding of signal 12SL includes front contacts 42 and 43 of lightout relay 12ULO. If the lamp of the upper signal is burned out, the contacts of relay 12ULO will be released and will cause the energy supplied

to the winding of signal 12SL to be of reverse polarity so that the signal mechanism will condition the signal to provide a yellow instead of a green light. This arrangement prevents the lower signal unit 12SL from displaying a green light when the lamp of the upper signal unit 12SU is burned out. This prevents the display of a single green light by a signal when the lamp of the upper signal unit is burned out, and causes a single yellow light to be displayed at such times. The single green light might be interpreted as a clear indication when the signal is intended to display its approach medium indication, while the single yellow light will be interpreted as a more restrictive indication than that intended to be displayed by the signal.

When the mechanism of signal 12SL responds to energization of the signal winding by current of normal polarity, front contact G of the signal is closed and establishes the circuit to supply energy to the relay 12LG so that contact 38 of this relay picks up and interrupts the supply of energy of 120 code frequency to transformer 11TT and establishes a circuit to supply energy of 180 code frequency thereto. This circuit is traced from terminal BX through contact 180 of the code transmitter, front contact 38 of relay 12LG, back contact 30 of relay 12UG, front contact 31 of relay 12H, and primary winding of transformer 11TT to terminal CX. The energy of 180 code frequency supplied to the rails of section 11T causes the signal for that section to provide its clear indication.

If the lamp of the upper signal unit is burned out so relay 12ULO is released and signal 12SL displays its yellow indication, relay 12LG will not be energized and its contact 38 will not establish the circuit for supplying energy of 180 code frequency to section 11T, but will maintain the circuit for supplying energy of 120 code frequency thereto. Accordingly, the signal for section 11T will not provide its clear indication but will display its approach medium indication, and a following train will receive a restrictive indication before it reaches the signal 12S at a time when that signal is displaying a single yellow light.

When the train under consideration vacates the section in advance of section 13T energy of 120 code frequency is supplied to the rails of section 13T and the signal 13S displays its approach medium indication, while energy of 180 code frequency is supplied to the rails of section 12T. This energy feeds to the track relay 12TR and operates it at a rate such that energy is no longer supplied through unit 120DU to relay 12K but is supplied through unit 180DU to relay 12J.

When relay 12J picks up, its contacts 21 and 22 interrupt the previously traced circuit for supplying energy of reverse polarity to the winding of signal 12SU and establish the circuit for supplying energy of normal polarity thereto, while contact 33 of relay 12J establishes the circuit for relay 12UG so that energy is supplied to this relay over the circuit which includes front contact G of the signal. When relay 12UG picks up, its contact 25 interrupts the circuit of signal 12SL and this signal displays a red light, while contact 30 of the relay 12UG interrupts one circuit for supplying energy of 180 code frequency to section 11T and establishes another circuit for supplying energy of 180 code frequency thereto.

When the energy supplied to section 12T is

changed from 120 to 180 code frequency the relay 12K releases and the relay 12J picks up. The relay 12K may release before the signal 12SU responds to picking up of relay 12J, and this system is arranged to prevent an undesirable flash of the approach indication at such times.

When energy of 120 code frequency is supplied to section 12T the relays 12H and 12K are picked up while the relay 12J is released so that energy of normal polarity is supplied to the winding of signal 12SL over the circuit which is traced from terminal B through front contact 28 of relay 12H, back contact 25 of relay 12UG, front contact 42 of relay 12ULO, front contact 40 of relay 12K, front contact 27 of relay 12UY, winding of signal 12SL, front contact 28 of relay 12UY, front contact 41 of relay 12K, front contact 43 of relay 12ULO, and front contact 23 of relay 12H to terminal C. Accordingly, the contact G of the signal is closed so energy is supplied to relay 12LG and its contacts are picked up.

On interruption of the supply of energy of 120 code frequency to section 12T the relay 12K releases and interrupts the circuit just traced for supplying energy to the winding of signal 12SL. However, on release of relay 12K, energy continues to be supplied to the signal 12SL over the circuit which includes front contacts 46 and 47 of relay 12LG and back contacts 40 and 41 of relay 12K. The relay 12LG is of a type the contacts of which are slow to release and they remain picked up for a period longer than is required for the contacts of relay 12J to pick up. Accordingly, after release of relay 12K the contacts of relay 12LG maintain the supply of energy to the winding of signal 12SL until the relay 12UG picks up and its contact 25 interrupts the circuit of the signal 12SL. When the relay 12J picks up it changes the polarity of the energy supplied to the winding of signal 12SU from reverse to normal so this signal displays a green light, while energy is supplied to relay 12UG so that it picks up and cuts off the supply of energy to signal 12SL so this signal provides a red light.

If on release of relay 12K prior to picking up of relay 12J the supply of energy to signal 12SL were interrupted, this signal would display a red light, while the upper signal 12SU still displays a yellow light so the signal 12S would momentarily display its approach indication consisting of a yellow light over a red light. The arrangement provided by this invention by which the slow releasing relay 12LG maintains the supply of energy to signal 12SL after release of relay 12K and prior to picking up of relay 12UG prevents the momentary display of the approach indication by the signal on a change from 120 to 180 code frequency and insures that the display of the approach medium indication will be maintained until the change to the clear indication occurs.

The system of this invention is arranged so that when a train moving in the reverse direction of traffic passes through the track stretch the signals will not momentarily display indications more restrictive than are required by traffic conditions.

When such a train enters the section in advance of section 13T the energy supplied to section 12T is changed from 180 code frequency to 120 code frequency and relay 12J releases and relay 12K picks up. On release of relay 12J its contact 33 interrupts the circuit of relay 12UG, but this relay is of a type which is slow in releas-

ing so that its contacts remain picked up for a period subsequent to release of the contacts of relay 12J. In addition, on release of the contacts of relay 12J its contacts 21 and 22 interrupt one circuit for supplying energy of normal polarity to the winding of signal 12SU, but energy of normal polarity continues to be supplied thereto over the circuit including front contacts 34 and 35 of relay 12UG and back contacts 21 and 22 of relay 12J.

On picking up of relay 12K its front contacts 40 and 41 are closed to permit energy to be supplied to the winding of signal 12SL when the contacts of relay 12UY are picked up.

After a short time interval, contacts 34 and 35 of relay 12UG release and interrupt the supply of energy of normal polarity to the winding of signal 12SU and establish the circuit to supply energy of reverse polarity thereto so that the signal mechanism conditions the signal to display a yellow light, while front contact Y of the signal is closed so energy is supplied to relay 12UY. On the supply of energy to relay 12UY its contacts 27 and 28 pick up and complete the circuit for supplying energy of normal polarity to the winding of signal 12SL and this signal is conditioned to provide a green light, while its front contact G is closed so that energy is supplied to relay 12LG. The circuit of relay 12LG is complete as contact 44 of relay 12K is picked up, and accordingly the contacts of relay 12LG pick up.

When the relay 12UG releases, its contact 39 interrupts the circuit for supplying energy of 180 code frequency to section 11T, while on picking up of relay 12UY its contact 37 establishes the circuit including back contact 38 of relay 12LG, back contact 30 of relay 12UG, and front contact 31 of relay 12H for supplying energy of 120 code frequency to section 11T. As soon as the signal 12SL displays its green light and relay 12LG picks up, contact 39 of relay 12LG interrupts the circuit for supplying energy of 120 code frequency to section 11T and establishes a circuit for supplying energy of 180 code frequency thereto. It will be seen, therefore, that in the time interval between the release of relay 12UG and picking up of relay 12LG, the supply of energy of 180 code frequency to section 11T is cut off, while energy of 120 code frequency is supplied to section 11T during this time. On interruption of the supply of energy of 180 code frequency to section 11T the relay 11J, not shown, for that section releases, but the relay 11UG, not shown, is slow enough in releasing to maintain the supply of energy of normal polarity to the upper unit of signal 11S for a period longer than the interruption in the supply of energy of 180 code frequency to section 11T. Accordingly, at this time signal 11S displays its clear indication at all times and there is no momentary display of a restrictive indication thereby.

The equipment operates in a similar manner on a change from the approach medium to the approach indication. When the train under consideration moving in the reverse direction enters section 13T the energy supplied to section 12T is changed from 120 code frequency to 75 code frequency with the result that relay 12K releases and its contact 44 interrupts the circuit of relay 12LG, while its contacts 43 and 44 interrupt one circuit for supplying energy to the winding of signal 12SL and establish the circuit including front contacts 46 and 47 of relay 12LG for supplying energy to the winding of signal 12SL. The relay 12LG, like the relay 12UG, is of a type the con-

tacts of which are slow to release, and its contacts remain picked up and maintain the circuit for supplying energy to the winding of signal 12SL for a period subsequent to release of the contacts of relay 12K. After a short time interval the 5 relay 12LG releases and its contacts 46 and 47 interrupt the supply of energy to the winding of signal 12SL, while its contact 38 interrupts the supply of energy of 180 code frequency to section 11T and establishes the circuit to supply energy of 120 code frequency thereto. On release of the relay 12LG and interruption of the supply of energy to the winding of signal 12SL the mechanism of this signal conditions the unit to provide its red light so signal 12S now displays its approach 15 indication consisting of a yellow light over a red light.

When the train under consideration enters section 12T relay 12H releases and its contacts 20 and 23 interrupt the supply of energy to the winding of signal 12SU, so this signal displays a red light, while contact 31 of relay 12H interrupts the supply of energy of 120 code frequency to section 11T and establishes the circuit to supply energy of 75 code frequency thereto. The signal 12S now displays its stop indication consisting of a red light over a red light.

From the foregoing it will be seen that the system provided by this invention is arranged so that changes in the signals either to a less restrictive indication or to a more restrictive indication occur without objectionable displays of other indications. Furthermore, it will be seen that this system is arranged so that the supply of coded energy to the section in the rear of a signal is governed by the signal repeater relays so that changes in this energy occur only when the signals respond to a change in the signal control relays.

Construction and operation of system shown in Fig. 2

In Fig. 2 of the drawings there is shown a modification of my invention adapted for use with signals arranged to provide five aspects. Except as hereinafter pointed out in detail, the system of Fig. 2 is the same as that shown in Fig. 1. This modification makes use of a special form of energy, designated 75M code frequency, to provide an additional proceed aspect. This 75M code may be the usual 75 code to which a distinguishing periodic characteristic which recurs every three cycles, for example, has been added. Suitable decoding means designated 75M decoding unit is provided to detect the presence of this code. The details of this decoding means are not essential for an understanding of this invention and any appropriate means may be employed for this purpose. One such means is shown in application Serial No. 452,902 of Carl Volz filed July 30, 1942, for Code detecting means. This decoding means controls the relay 12HB in such manner that the relay 12HB is energized when and only when the track relay is responding to energy of 75M code frequency.

This modification further differs from that shown in Fig. 1 in that a relay 12LY is provided which is energized when lower signal 12SL is displaying a yellow light.

The equipment is shown in the condition which it assumes when the track stretch is vacant. At this time, energy of 180 code frequency is supplied to the transformer 12TT and feeds to the track relay 12TR so that energy is supplied through the decoding transformer 12DT to re-

lay 12HA and to relay 12J through the resonant rectifier unit 180DU. Accordingly, energy of normal polarity is supplied to the winding of signal 12SU over the circuit which is traced from terminal B through front contact 20 of relay 12HA, front contact 21 of relay 12J, winding of signal 12SU, front contact 22 of relay 12J, and front contact 23 of relay 12HA to terminal C. The signal 12SU, therefore, displays its green light, while its contact G is closed to establish the circuit of relay 12UG so that contact 25 of relay 12UG is picked up and interrupts the circuit of the winding of signal 12SL. The signal 12SL, therefore, displays a red light while the signal 12S displays its clear indication consisting of a green light over a red light.

At this time, energy of 180 code frequency is supplied to transformer 11TT over the circuit which is traced from terminal BX through contact 180 of the code transmitter 12CT, front contact 30 of relay 12UG, front contact 31 of relay 12HA, and primary winding of transformer 11TT to terminal CX.

When a train moving in the normal direction of traffic enters section 12T the track relay 12TR ceases to follow code and relays 12HA and 12J release. On release of relay 12HA its contacts 20 and 23 interrupt the supply of energy to the winding of signal 12SU so this signal displays a red light, while contact 31 of relay 12HA interrupts the supply of energy of 180 code frequency to transformer 11TT and establishes the circuit to supply energy of 75 code frequency thereto. At this time, relay 12UG releases.

When the train enters section 13T the equipment for that section operates to cause signal 13S to display its stop indication, while energy of 75 code frequency is supplied to the transformer 12TT.

When the train vacates section 12T this energy feeds to relay 12TR which causes energy to be supplied through the decoding transformer 12DT to relay 12HA, but not to the other signal control relays. On picking up of relay 12HA its contact 31 interrupts the supply of energy of 75 code frequency to section 11T, while energy of reverse polarity is supplied to the winding of signal 12SU over the circuit which includes front contacts 20 and 23 of relay 12HA, back contacts 34 and 35 of relay 12UG, and back contacts 21 and 22 of relay 12J. Accordingly, the signal 12SU now displays a yellow light, while contact Y of the signal establishes the circuit of relay 12UY with the result that this relay picks up and its contact 37 establishes the circuit for supplying energy of 75M code frequency to section 11T. The circuit for supplying energy of 75M code frequency to section 11T is traced from terminal BX through contact 75M of the code transmitter 12CT, back contact 49 of relay 12LY, front contact 37 of relay 12UY, back contact 38 of relay 12LG, back contact 30 of relay 12UG, front contact 31 of relay 12HA, and primary winding of transformer 11TT to terminal CX.

At this time the upper unit 12SU of signal 12S displays a yellow light while the lower unit 12SL of the signal continues to display a red light. The signal 12S, therefore, displays its approach indication consisting of a yellow light over a red light.

When the train vacates section 13T, energy of 75 code frequency is supplied to the track relay for that section so that signal 13S displays its approach indication, while energy of 75M code frequency is supplied to section 12T. When this

energy is supplied to the track relay 12TR, energy continues to be supplied through the decoding transformer 12DT to relay 12HA, while energy is also supplied through the 75M decoding unit to the relay 12HB. On picking up of the relay 12HB, energy of reverse polarity is supplied to the winding of signal 12SL over the circuit which is traced from terminal B through front contact 20 of relay 12HA, back contact 25 of relay 12UG, front contact 50 of relay 12HB, back contact 47 of relay 12LG, back contact 41 of relay 12K, front contact 28 of relay 12UY, winding of signal 12SL, front contact 21 of relay 12UY, back contact 40 of relay 12K, back contact 46 of relay 12LG, front contact 51 of relay 12HB, and front contact 23 of relay 12HA to terminal C. Accordingly, the signal unit 12SL displays a yellow light so the signal 12S displays its advance approach indication consisting of a yellow light over a yellow light. In addition, contact Y of signal 12SL establishes the circuit of relay 12LY and its contact 49 picks up to interrupt the supply of energy of 75M code frequency to section 11T and cause energy of 120 code frequency to be supplied thereto.

When the train vacates the section in advance of section 13T, energy of 75M code frequency is supplied to the rails of section 13T, and the equipment for that section causes energy of 120 code frequency to be supplied to section 12T. When this energy is supplied to the track relay 12TR, energy is no longer supplied through the 75M decoding unit to relay 12HB, but energy is now supplied through the resonant unit 120DU to relay 12K.

On picking up of relay 12K its contacts 40 and 41 interrupt the circuit for supplying energy of reverse polarity to signal 12SL and establish the circuit traced in connection with the system shown in Fig. 1 for supplying energy of normal polarity to the signal 12SL. The signal unit 12SL now displays a green light so signal 12S displays its approach medium indication consisting of a yellow light over a green light. At this time, contact Y of signal 12SL is opened while contact G is closed and establishes the circuit to supply energy to relay 12LG. When relay 12LG picks up, its contact 38 interrupts the supply of energy of 120 code frequency to section 11T and establishes a circuit to supply energy of 180 code frequency thereto.

When the train vacates the second section in advance of section 13T, energy of 180 code frequency is supplied to section 12T with the result that relay 12K releases and relay 12J picks up. When relay 12J picks up, its contacts 21 and 22 change the energy supplied to signal 12SU from reverse to normal polarity. The signal 12SU now displays a green light, while its contact Y interrupts the circuit of relay 12UY and its contact G establishes the circuit of relay 12UG. Release of relay 12UY interrupts the circuit of signal 12SL, while this circuit is additionally interrupted by contact 25 of relay 12UG. The signal 12S now displays its clear indication comprising a green light over a red light.

This modification operates in the same manner as that shown in Fig. 1 to prevent an objectionable signal flash on a change in the energy supplied to a section from 120 to 180 code frequency, or from 180 to 120 code frequency and a detailed description thereof is unnecessary.

This modification also operates to prevent an objectionable signal flash on a change from 120 to 75M code. When energy of 120 code is supplied to section 12T, relays 12HA and 12K are

picked up so energy of reverse polarity is supplied to signal 12SU and energy of normal polarity is supplied to signal 12SL. Accordingly, relays 12LG and 12UY are picked up.

On the change to energy of 75M code frequency the relay 12K releases and the relay 12HB picks up. The operating characteristics of the 75M decoding means are such, however, that the relay 12HB may not pick up until after the relay 12K releases. On release of relay 12K its contacts 40 and 41 interrupt one circuit for supplying energy of normal polarity to the winding of signal 12SL, but the supply of energy of this polarity to the signal is maintained over the circuit which includes front contacts 46 and 47 of relay 12LG, and back contacts 49 and 41 of relay 12K. The signal, therefore, continues to display a green light. When relay 12K releases, its contact 44 interrupts the circuit of relay 12LG, but the relay 12LG is of a type which is slow to release and hence its contacts remain picked up for a period of time. This period is long enough for the relay 12HB to become picked up. Accordingly, on release of the relay 12LG the contacts of relay 12HB are picked up and energy of reverse polarity is supplied to the winding of signal 12SL so that this signal displays a yellow light. If the circuit established by front contacts 46 and 47 of relay 12LG and back contacts 40 and 41 of relay 12K were not provided, the signal unit 12SL would be deenergized in the period between release of relay 12K and picking up of relay 12HB and would display a red light so that signal 12S would improperly display its approach indication consisting of a yellow light over a red light. The circuit provided by the back contacts of relay 12K and the front contacts of relay 12LG insures that signal 12SL will continue to display its green light until the circuit for supplying energy of reverse polarity to the signal is established to thereby insure that the signal will change from its green to its yellow aspect without delay.

The system of Fig. 2 is also arranged so that on a change in the energy supplied to a section from 180 code frequency to 75M code frequency a long display of the approach indication is prevented.

When energy of 180 code frequency is supplied to section 12T, relays 12HA and 12J are picked up and energy of normal polarity is supplied to the winding of the signal 12SU. This signal, therefore, displays a green light, while its contact G establishes the circuit of relay 12UG so that the contacts of this relay are picked up and its contact 25 interrupts the circuit of signal 12SL.

On the change in the energy supplied to section 12T from 180 to 75M code frequency the relay 12J releases while the relay 12HB picks up. On release of relay 12J its contacts 21 and 22 interrupt one circuit for supplying energy of normal polarity to signal 12SU, but they establish the circuit including front contacts 34 and 35 of relay 12UG for supplying energy of normal polarity to signal 12SU so this signal continues to display its green light. On release of the relay 12J its contact 33 interrupts the energizing circuit for relay 12UG, but because of the slow releasing characteristics of the relay 12UG its contacts remain picked up for a period of time and maintain the supply of energy to the signal 12SU. The relay 12UG is selected so that its contacts will remain picked up until after the relay 12HB picks up.

Accordingly, on release of relay 12UG the en-

ergy supplied to signal 12SU is changed from normal to reverse polarity, while contact 25 of relay 12UG establishes the circuit to supply energy of reverse polarity to the winding of signal 12SL. The circuit for supplying energy to signal 12SL is complete as soon as signal 12SU responds to the energy of reverse polarity and establishes the circuit of relay 12UY so that its contacts pick up. As a result the signal 12SL will display a yellow light very soon after signal 12SU displays a yellow light, and the signal 12S 5 will display its yellow over red or approach indication for only a very short period.

The system shown in Fig. 2, like that shown in Fig. 1, is arranged so that the supply of energy to the section in the rear is controlled by the signal repeater relays so that changes in this energy occur only if the signals respond to operation of the signal control relays. Similarly, in this modification, the lightout relay 12ULO controls the supply of energy to the winding of the signal 12SL to prevent the display of a green light by this signal when the lamp of the upper signal unit is burned out.

Construction and operation of system shown in Fig. 3

In Fig. 3 there is shown a modified arrangement which I may employ to control four aspect wayside signals. This modification differs from that shown in Fig. 1 in that it employs a checking relay CR to control the supply of energy to the section in the rear. The checking relay CR is controlled by the lightout relay, and by the signal control and signal repeater relays so as to be energized only if the lightout relay is energized, and if the signal control relays and the signal repeater relays are in correspondence. The relay CR, when released, causes energy of 75 40 code frequency to be supplied to the section in the rear, and prevents the supply of energy of 120 or 180 code to the section in the rear.

The system shown in Fig. 3 is shown in the condition which it assumes when the track stretch is vacant. At this time, energy of 180 code frequency is supplied to the rails of section 12T and track relay 12TR causes energy to be supplied through the decoding transformer 12DT to the relay 12H and through the resonant rectifier unit 180DU to the relay 12J. As these relays are picked up, energy of normal polarity is supplied to the winding of signal 12SU over the circuit which includes front contacts 20 and 23 of relay 12H and front contacts 21 and 22 of relay 12J, and this signal unit displays a green light while its front contact G establishes the circuit to supply energy to relay 12UG.

At this time, checking relay 12CR is energized over the circuit which is traced from terminal B through front contact 20 of relay 12H, front contact 60 of relay 12J, back contact 61 of relay 12UY, back contact 62 of relay 12LG, front contact 63 of relay 12UG, front contact 64 of relay 12ULO, and winding of relay 12CR to terminal C.

Energy of 180 code frequency is supplied to the section in the rear over the circuit which is traced from terminal BX through contact 180 of the code transmitter 12CT, front contact 66 of relay 12J, front contact 67 of relay 12CR, front contact 31 of relay 12H, and primary winding of transformer 11TT to terminal CX.

As the relay 12K is released, its contacts 70 and 71 interrupt the circuit of signal unit 12SL and it displays a red light, while the signal 12S pro-

vides its clear indication consisting of a green over a red light.

When a train moving in the normal direction of traffic enters section 12T the track relay 12TR is shunted and energy is no longer supplied through the decoding transformer 12DT to the relays 12H and 12J. On release of relay 12H its contacts 20 and 23 interrupt the supply of energy to the signal 12SU so that this signal displays its red indication, while its contact G interrupts the circuit of the relay 12UG. In addition, contacts 20 and 23 of relay 12H prevent the supply of energy to the winding of signal 12SL, while contact 20 of relay 12H interrupts the supply of energy to relay 12CR, and contact 31 of relay 12H interrupts the supply of energy of 180 code frequency to the section in the rear and establishes the circuit for supplying energy of 75 code frequency thereto. As the signals 12SU and 12SL are both deenergized, the signal 12S displays its stop indication consisting of a red light over a red light.

At this time the circuit of relay 12CR is interrupted and the contact 67 of this relay is released.

When the train enters section 13T the equipment for that section operates to cause signal 13S to display its stop indication and to cause energy of 75 code frequency to be supplied to the transformer 12TT. When the train vacates section 12T this energy feeds to the track relay 12TR and it causes energy to be supplied through the decoding transformer 12DT to relay 12H, but not to relays 12K and 12J. When relay 12H picks up, its contacts 20 and 23 establish the circuit including back contacts 21 and 22 of relay 12J for supplying energy of reverse polarity to the winding of signal 12SU so this signal displays a yellow light, while its contact Y is closed so that energy is supplied to the relay 12UY and its contacts pick up and establish a circuit to supply energy to the checking relay 12CR. This circuit is traced from terminal B through front contact 20 of relay 12H, back contact 60 of relay 12J, back contact 74 of relay 12K, front contact 73 of relay 12UY, back contact 72 of relay 12LG, back contact 63 of relay 12UG, front contact 64 of relay 12ULO, and winding of relay 12CR to terminal C.

When the relay 12H picks up, the back point of contact 31 interrupts the circuit for supplying energy of 75 code frequency to section 11T and the front point of this contact establishes another circuit including back contact 67 of relay 12CR for supplying energy of 75 code frequency to section 11T. As soon as the signal 12SU displays its yellow aspect and establishes the circuit of relay 12UY so that its picks up and establishes the circuit of relay 12CR, the contact 67 of relay 12CR interrupts the supply of energy of 75 code frequency to section 11T and establishes the circuit for supplying energy of 120 code frequency thereto. This circuit is traced from terminal BX through contact 120 of the code transmitter 12CT, back contact 76 of relay 12K, back contact 68 of relay 12J, front contact 67 of relay 12CR, front contact 31 of relay 12H, and primary winding of transformer 11TT to terminal CX. At this time, therefore, the signal 12S displays its approach indication consisting of a yellow light over a red light, while energy of 120 code frequency is supplied to the section in the rear.

If for any reason on picking up of the relay 12H the signal 12S fails to respond and to dis-

play its yellow light, the checking relay 12CR will not be energized and will maintain the supply of energy of 75 code frequency to the section in the rear so that a train approaching the signal 12S at a time when the signal is defective will receive the most restrictive proceed indication from the signal for section 11T, while if cab signal apparatus is used, a locomotive present in section 11T will also receive its most restrictive proceed indication in the cab.

When the train advances far enough to vacate section 13T the equipment for that section operates to cause signal 13S to provide its approach indication, while energy of 120 code frequency is supplied to section 12T. When the track relay 12TR responds to energy of 120 code frequency, energy is supplied through the decoding transformer 12DT to the relay 12H and is also supplied through the resonant unit 120DU to the relay 12K. When the contacts 70 and 71 of relay 12K are picked up, energy of normal polarity is supplied to the winding of signal 12SL, assuming that the contacts of relay 12ULO are picked up. On the supply of energy of normal polarity to the winding of the signal 12SL the signal displays a green light, while contact G of the signal is closed and energy is supplied to the relay 12LG.

On picking up of the relay 12K its contact 76 interrupts the circuit for supplying energy of 120 code frequency to section 11T and establishes a circuit for supplying energy of 180 code frequency thereto. This circuit is traced from terminal BX through contact 180 of the code transmitter, front contact 76 of relay 12K, back contact 66 of relay 12J, front contact 67 of relay 12CR, front contact 31 of relay 12H, and primary winding of transformer 11TT to terminal CX.

On picking up of relay 12K its contact 74 interrupts the previously traced circuit for supplying energy to the relay 12CR, but another circuit for supplying energy to that relay is completed on picking up of relay 12LG. This circuit is traced from terminal B through front contact 20 of relay 12H, back contact 60 of relay 12J, front contact 74 of relay 12K, front contact 77 of relay 12UY, front contact 72 of relay 12LG, back contact 63 of relay 12UG, front contact 64 of relay 12ULO, and winding of relay 12CR to terminal C. The relay 12CR is of a type the contacts of which are slow to release, and the relay is selected so that its contacts will remain picked up in the interval between picking up of the contacts of relay 12K and picking up of relay 12LG. Accordingly, contact 67 of relay 12CR remains picked up and maintains the circuit for supplying energy of 180 code frequency to section 11T.

At this time the signal 12S displays its approach medium indication consisting of a yellow light over a green light. If on picking up of the relay 12K the signal 12SL fails to respond to provide a green light the relay 12LG will remain released, and will not establish the circuit of relay 12CR so that this relay will release and its contact 67 will interrupt the circuit for supplying energy of 180 code frequency to section 11T and will establish a circuit for supplying energy of 75 code frequency thereto.

When the train advances far enough to vacate the section in advance of section 13T energy of 120 code frequency is supplied to the rails of section 13T and the equipment for that section operates to supply energy of 180 frequency to sec-

tion 12T. On the supply of this energy to the relay 12TR, energy continues to be supplied through the decoding transformer 12DT to the relay 12H, while energy is now supplied to the relay 12J, but not to the relay 12K.

On picking up of the relay 12J its contacts 21 and 22 change the polarity of the energy supplied to the winding of signal 12SU from reverse to normal, and the mechanism of this signal conditions the signal to display a green light, while contact Y of the signal interrupts the circuit of relay 12UY and contact G of the signal establishes the circuit of the relay 12UG.

On release of relay 12K its contacts 70 and 71 interrupt the circuit of the winding of signal 12SL and this signal displays its red light, while its contact G interrupts the circuit of relay 12LG.

On picking up of relay 12J or release of relay 12K, whichever occurs first, the circuit of relay 12CR is interrupted, while after the signals complete their changes, and the signal repeater relays respond to these changes, energy is supplied to relay 12CR over the circuit originally traced for this relay. The relay 12CR is sufficiently slow releasing to remain picked up during this change in the signals.

On picking up of the relay 12J its contact 66 interrupts one circuit for supplying energy of 180 code frequency to section 11T, and establishes another circuit for supplying energy of 180 code frequency thereto.

If the signals fail to respond to the changes in the signal control relays, or if the signal repeater relays fail to respond to the changes in the signals, the circuit of the relay 12CR will be interrupted and contact 67 of this relay will release and cut off the supply of energy of 180 code frequency to section 11T and establish a circuit for supplying energy of 75 code frequency thereto.

This modification employs a lightout relay 12ULO to check the filament of the lamp of the upper signal 12SU. This relay governs the polarity of the energy supplied to the winding of the lower signal 12SL to prevent the display of a green light by this signal at a time when the lamp of the upper signal is burned out. The lightout relay 12ULO also controls the circuit of checking relay 12CR so that when the lightout relay is released, relay 12CR is also released and its contact 67 causes energy of 75 code frequency to be supplied to section 11T. Accordingly, when the lamp of the upper signal is burned out the lower signal cannot display its green light, while energy of 75 code frequency will be supplied to the section in the rear so that the signal for that section will display its most restrictive proceed indication and a train approaching the defective signal will do so at reduced speed.

It will be seen that this modification of the invention is arranged so that except for the control by the lightout relay of the polarity of the energy supplied to the winding of the lower signal unit, the circuits of the windings of the signal units are controlled only by the signal control relays. This arrangement makes it unnecessary for changes in the lower signal unit to await changes in the upper signal unit and in the repeater relays for the upper signal unit, but permits the lower signal unit to respond immediately to a change in position of the control relay 12K.

As the signal units respond promptly to changes in the control relays, the signal will not display objectionable aspects on a change in the signal

control relays and it is not necessary to provide means to prevent these signal flashes.

In addition, the checking relay 12CR checks correspondence between the signal control relays and signal repeater relays and controls the supply of coded energy to the section in the rear. This permits the supply of coded energy to the section in the rear to be controlled by the signal control relays so that changes in the energy supplied to the section in the rear occur promptly.

Construction and operation of system shown in Fig. 4

In Fig. 4 of the drawings there is shown a modification of this invention adapted for use where the wayside signals are arranged to provide five different aspects. This modification is similar to that shown in Fig. 3 and employs a checking relay CR which is governed by the signal control relays, the signal repeater relays, and the light-out relays. This modification differs from that shown in Fig. 3 in that lightout relays are provided for both the upper and lower signals, while this modification is similar to those shown in Figs. 1 and 2 as it employs means governed by the signal repeater relays to delay changes in the signals. This modification is also like that shown in Fig. 2 as it employs energy of 75M code frequency and has means for detecting this energy.

The system of Fig. 4 is shown in the condition which it assumes when the track stretch is vacant. At this time, energy of 180 code frequency is supplied to the rails of section 12T and the track relay 12TR causes energy to be supplied through the decoding transformer 12DT to the relay 12HA and through the resonant rectifier unit 180DU to relay 12J. As the relays 12HA and 12J are picked up, energy of normal polarity is supplied to the winding of signal 12SU over the circuit which includes front contacts 20 and 23 of relay 12HA and front contacts 21 and 22 of relay 12J, so signal 12SU provides a green light while its contact G establishes the circuit to supply energy to the relay 12UG. At this time the circuit of the winding of signal 12SL is interrupted by contacts 50 and 51 of relay 12HB so signal 12SL provides a red light and the signal repeater relays 12LG and 12LY are both released. The signal 12S, therefore, provides its clear indication consisting of a green light over a red light.

It is assumed that the filaments of the lamps of the signals are intact so the lightout relays 12ULO and 12LLO are both energized. Under these conditions the checking relay 12CR is energized over the circuit which is traced from terminal B through front contact 20 of relay 12HA, front contact 60 of relay 12J, back contact 61 of relay 12UY, back contact 62 of relay 12LG, back contact 85 of relay 12LY, front contact 63 of relay 12UG, front contact 64 of relay 12ULO, front contact 86 of relay 12LLO, and winding of relay 12CR to terminal C.

At this time, energy of 180 code frequency is supplied to section 11T over the circuit which is traced from terminal BX through contact 180 of the code transmitter 12CT, front contact 99 of relay 12J, front contact 67 of relay 12CR, front contact 31 of relay 12HA, and primary winding of transformer 11TT to terminal CX.

When a train moving in the normal direction of traffic enters section 12T the track relay 12TR is shunted and energy is no longer supplied through the decoding transformer 12DT to the relays 12HA and 12J. On release of relay 12HA

its contacts 20 and 23 cut off the supply of energy to the signal 12SU and this signal displays a red light, while relay 12UG releases. In addition, at this time the circuit of relay 12CR is interrupted and its contact 61 releases, while contact 31 of relay 12HA cuts off the supply of energy of 180 code frequency to section 11T and causes energy of 75 code frequency to be supplied thereto.

At this time, therefore, signal 12S displays its stop indication consisting of a red light over a red light, while energy of 75 code frequency is supplied to the section in the rear.

When the train enters section 13T the signal for that section displays its stop indication and energy of 75 code frequency is supplied to transformer 12TT. When the train vacates section 12T this energy feeds to the track relay 12TR and operates it so that energy is supplied through the decoding transformer 12DT to relay 12HA and its contacts pick up with the result that energy of reverse polarity is supplied to the winding of the signal 12SU. The circuit for supplying energy to the signal 12SU is traced from terminal B through front contact 20 of relay 12HA, back contact 34 of relay 12UG, back contact 22 of relay 12J, winding of signal 12SU, back contact 21 of relay 12J, back contact 35 of relay 12UG, and front contact 23 of relay 12HA to terminal C. The signal 12SU, therefore, displays a yellow light, and its contact Y establishes the circuit of the relay 12UY, while the signal 12S provides its approach indication consisting of a yellow light over a red light.

When the relay 12UY picks up it completes a circuit for supplying energy to the checking relay 12CR. This circuit is traced from terminal B through front contact 20 of relay 12HA, back contact 60 of relay 12J, back contact 81 of relay 12K, back contact 88 of relay 12HB, back contact 89 of relay 12LY, front contact 99 of relay 12UY, back contact 91 of relay 12LG, back contact 63 of relay 12UG, front contact 64 of relay 12ULO, front contact 86 of relay 12LLO, and winding of relay 12CR to terminal C. Accordingly, if on picking up of relay 12HA, the signal 12SU responds in the proper manner and relay 12UY is energized a circuit for the relay 12CR will be established.

When the relays 12HA and 12CR are both picked up the supply of energy of 75 code frequency to section 11T is cut off, and energy of 75M code frequency is supplied thereto over the circuit which is traced from terminal BX through contact 75M of the code transmitter 12CT, back contact 94 of relay 12HB, back contact 95 of relay 12K, back contact 99 of relay 12J, front contact 67 of relay 12CR, front contact 31 of relay 12HA, and primary winding of transformer 11TT to terminal CX.

When the train advances far enough to vacate section 13T the equipment for that section operates to supply energy of 75M code frequency to section 12T. When energy of this frequency is supplied to track relay 12TR energy continues to be supplied through the decoding transformer 12DT to the relay 12HA, while energy is now supplied through the 75M decoding unit to the relay 12HB.

When relay 12HB picks up, its contacts 50 and 51 establish the circuit to supply energy of reverse polarity to the winding of signal 12SL. This circuit is traced from terminal B through front contact 20 of relay 12HA, front contact 50 of relay 12HB, back contact 41 of relay 12LG, back contact 41 of relay 12K, winding of signal

12SL, back contact 40 of relay 12K, back contact 46 of relay 12LG, front contact 51 of relay 12HB, and front contact 23 of relay 12HA to terminal C. Accordingly, the signal 12SL will establish a yellow light and its contact Y will indicate the circuit of relay 12LY, while the signal 12S now displays its advance approach indication consisting of a yellow light over a yellow light.

When the relay 12HB picks up, its contact 88 10 interrupts the previously traced circuit for supplying energy to the relay 12CR, but the circuit of this relay is reestablished when relay 12LY picks up. This circuit is the same as that previously traced for relay 12CR, except that it includes the front points of contacts 88 and 89 15 instead of the back points of these contacts of relays 12HB and 12LY. The relay 12CR is slow enough in releasing to remain picked up throughout the interval in which the supply of energy to 20 the relay 12CR is interrupted.

On picking up of the relay 12HB its contact 94 25 interrupts the circuit for supplying energy of 75M code frequency to section 11T and establishes the circuit for supplying energy of 120 code frequency thereto. This circuit is traced from terminal BX through contact 120 of the code transmitter 12CT, front contact 94 of relay 12HB, back contact 95 of relay 12K, back contact 99 of relay 12J, front contact 67 of relay 12CR, front contact 31 of relay 12HA, and primary winding of transformer 11TT to terminal CX.

When the train advances far enough to vacate the section in advance of section 13T energy of 120 code frequency is supplied to section 12T and the track relay 12TR operates at a rate such that energy is no longer supplied to relay 12HB, but is supplied to relay 12K, while relay 12HA remains picked up. On picking up of the relay 12K 40 its contacts 40 and 41 cut off the supply of energy of reverse polarity to the winding of signal 12SL and establish the circuit for supplying energy of normal polarity thereto. This circuit is traced from terminal B through front contact 20 of relay 12HA, front contact 42 of relay 12ULO, front contact 40 of relay 12K, winding of signal 12SL, front contact 41 of relay 12K, front contact 43 of relay 12ULO, and front contact 23 of relay 12HA to terminal C. The signal 12SL now displays a green light, while the signal 12S displays its approach medium indication consisting of a yellow light over a green light.

When signal 12SL displays a green light its contact Y interrupts the circuit of relay 12LY 50 and its contact G establishes the circuit of the relay 12LG.

On picking up of the relay 12K its contact 95 55 interrupts the circuit for supplying energy of 120 code frequency to section 11T and establishes a circuit for supplying energy of 180 code frequency thereto. This circuit is traced from terminal BX through contact 180 of the code transmitter 12CT, front contact 95 of relay 12K, back contact 99 of relay 12J, front contact 67 of relay 12CR, front contact 31 of relay 12HA, and primary winding of transformer 11TT to terminal CX.

On picking up of the relay 12K its contact 87 60 interrupts the circuit for supplying energy to the relay 12CR, while this circuit is additionally interrupted by contact 88 of relay 12HB when that relay releases. Another circuit is established for supplying energy to relay 12CR when the changes in the equipment are completed. This circuit is traced from terminal B through front 70 contact 20 of relay 12HA, back contact 68 of relay 12J, front contact 87 of relay 12K, back contact 97 of relay 12LY, front contact 93 of relay 12UY, front contact 91 of relay 12LG, back contact 63 of relay 12UG, front contact 64 of relay 12ULO, front contact 86 of relay 12LL0, and winding of relay 12CR to terminal C. The relay 12CR is slow enough in releasing to remain picked up during the period in which the circuit of the relay is interrupted, so its contact 67 maintains the circuit for supplying energy of 180 code frequency to section 11T.

When the train advances far enough to vacate the second section in advance of section 13T energy of 180 code frequency is supplied to section 12T, and the track relay 12TR operates at a rate such that energy is supplied to relay 12J, but is not supplied to relay 12K, while energy continues to be supplied to relay 12HA.

On picking up of relay 12J its contacts 21 and 22 20 interrupt the supply of energy of reverse polarity to the winding of signal 12SU and establish the circuit to supply energy of normal polarity thereto. On release of relay 12K its contacts 40 and 41 interrupt the supply of energy to the winding of signal 12SL. Accordingly, the signal 12S now displays its clear indication consisting of a green light over a red light.

When relay 12J picks up, its contact 99 30 interrupts one circuit for supplying energy of 180 code frequency to section 11T, and establishes the other circuit for supplying energy of this frequency to section 11T.

As signal 12SU is displaying a green light, relay 12UY is released and relay 12UG is picked up, while as signal 12SL is displaying a red light the relays 12LY and 12LG are both released, and energy is supplied to relay 12CR over the circuit originally traced for this relay.

This modification of the invention includes means governed by the green repeater relays for the signal units to delay changes in the signal units and thus prevent an objectionable display of the approach or yellow over red aspect by the signal when the signal is changing from its clear or its approach medium indication to its advance approach indication.

When energy of 180 code frequency is supplied to section 12T, relays 12HA and 12J are picked up and signal 12SU displays a green light while relay 12UG is picked up. At this time, energy of normal polarity is supplied to the winding of signal 12SU over the circuit which includes front contacts 20 and 23 of relay 12HA and front contacts 21 and 22 of relay 12J.

As a result of changes in traffic conditions in advance the energy supplied to section 12T may be changed from 180 code frequency to 75M code frequency. On this change in the energy supplied in section 12T, energy is no longer supplied to relay 12J, but is now supplied through the 75M decoding unit to the relay 12HB, while relay 12HA remains energized. However, if the 75M code is such that its distinguishing characteristic occurs only once every three cycles, there may be a short time interval between the time the supply of energy of 75M code frequency to section 12T is initiated, and the time at which relay 12HB picks up. Accordingly, the relay 12HB may not pick up until after the relay 12J releases.

On release of relay 12J its contacts 21 and 22 75 interrupt one circuit for supplying energy of normal polarity to the winding of signal 12SU and establish another circuit including front contacts 35 and 34 of relay 12UG and back contacts 21

and 22 of relay 12J for supplying this energy. In addition, on release of relay 12J its contact 33 interrupts the circuit of relay 12UG, but the relay 12UG is of a type which is slow to release so its contacts remain picked up and maintain the supply of energy of normal polarity to the winding of signal 12SU for a period subsequent to the release of relay 12J. Accordingly, the signal 12SU continues to display a green light during the transient interval.

When relay 12HB picks up, energy of reverse polarity is supplied to the winding of signal 12SL over the circuit which is traced from terminal B through front contact 20 of relay 12HA, front contact 50 of relay 12HB, back contact 47 of relay 12LG, back contact 41 of relay 12K, winding of signal 12SL, back contact 40 of relay 12K, back contact 46 of relay 12LG, front contact 51 of relay 12HB, and front contact 23 of relay 12HA to terminal C. The signal 12SL, therefore, displays a yellow light.

On release of the relay 12UG the supply of energy of normal polarity to signal 12SU is cut off and energy of reverse polarity is supplied thereto over the circuit which includes back contacts 34 and 35 of relay 12UG and back contacts 21 and 22 of relay 12J. Accordingly, the signal 12SU displays a yellow light instead of a green light, and as the upper and lower units of signal 12S both display yellow lights the signal provides its advance approach indication.

The various parts of the apparatus are arranged and selected so that the contacts of relay 12UG remain picked up to cause signal 12SU to continue to display a green light until signal 12SL has been conditioned to display its yellow light. This prevents the possible momentary display of a yellow over a red light by the signal 12S at this time. Such a signal would be interpreted by the engineman of an approaching train as indicating less favorable traffic conditions than actually exist and might cause him to unnecessarily effect an emergency application of the brakes. This system prevents the momentary display of the approach indication at these times and thus eliminates possible delays in train movements.

The equipment operates in a similar manner to prevent a momentary display of the approach indication on a change in the signal aspect from the approach medium to the advance approach indication.

When energy of 120 code frequency is supplied to section 12T, the relays 12HA and 12K are picked up, while energy of reverse polarity is supplied to the winding of signal 12SU, and energy of normal polarity is supplied to the winding of signal 12SL. As the signal 12SL displays a green light its contact G establishes the circuit of the relay 12LG.

When the energy supplied to section 12T is changed from 120 to 75M code frequency the relay 12K releases and the relay 12HB picks up. On release of relay 12K its contacts 40 and 41 interrupt one circuit for supplying energy of normal polarity to the winding of signal 12SL, but they establish a circuit including front contacts 46 and 47 of relay 12LG for supplying energy of normal polarity to the signal 12SL so this signal continues to display a green light.

On release of relay 12K its contact 44 interrupts the circuit of relay 12LG, but the relay 12LG is of a type the contacts of which are slow to release so they remain picked up after release of relay 12K and maintain the supply of energy to the winding of relay 12SL.

On picking up of relay 12HB its contacts 50 and 51 establish the circuit to supply energy of reverse polarity to the winding of signal 12SL on release of relay 12LG. Accordingly, on release of relay 12LG the supply of energy of normal polarity to the winding of signal 12SL is cut off, but energy of reverse polarity is supplied thereto so the mechanism of signal 12SL immediately conditions the signal to display a yellow light instead of a green light, and the signal 12S now provides its advance approach indication consisting of a yellow light over a yellow light.

The various parts of the apparatus are arranged and selected so that on the change in the energy supplied to section 12T from 120 to 75M code frequency the relay 12LG remains picked up until after the relay 12HB picks up. This insures that on release of relay 12LG and consequent cutting off of the supply of energy of normal polarity to signal 12SL, energy of reverse polarity will be supplied thereto and the signal will display a yellow light and there will be no time interval during which the signal displays a red light.

If the circuit including the front contacts 46 and 47 of relay 12LG for supplying energy of normal polarity to the signal 12SL is not provided, the signal winding will be deenergized if relay 12K releases before relay 12HB picks up. Under such circumstances the signal 12SL will display a red light until the relay 12HB picks up and during this interval the signal 12S will display its approach indication consisting of a yellow light over a red light. This is a more restrictive indication than is required by traffic conditions and may unnecessarily delay traffic. The system of this invention eliminates the momentary display of the approach indication and thus prevents traffic delays.

In the modification shown in Fig. 4 the circuit for supplying energy to checking relay 12CR is controlled by contacts of the lightout relays for both the upper and lower signal units so that if the lamp of either of these units is burned out the checking relay 12CR will be released and will cause the energy supplied to section 11T to be of 75 code frequency. Accordingly, under these conditions the signal for section 11T will display its most restrictive proceed indication and trains will approach the defective signal at reduced speed.

Similarly, if for any reason there is a disagreement between the signal control relays and the signal repeater relays, the circuit of the relay 12CR will be interrupted and this relay will cause energy of 75 code frequency to be supplied to section 11T.

The modification shown in Fig. 4, like the other modifications of the invention, has the circuit for supplying energy to the winding of signal 12SL controlled by the lightout relay 12ULO to prevent the supply of energy of normal polarity to this signal, and consequent display of a green light by this signal, at a time when the lamp of the upper signal 12SU is burned out.

Although I have herein shown and described only four forms of railway signaling systems embodying my invention, it is understood that various changes and modifications may be made therein within the scope of the appended claims without departing from the spirit and scope of my invention.

Having thus described my invention, what I claim is:

1. In combination, a section of railway track, 75 a control relay governed by traffic conditions in

said section, a slow releasing relay, a light signal for said section, said signal being of a type which has a member biased to a first position in which it conditions the signal to provide one indication and having a winding effective when energized to move said member to a second position in which it conditions the signal to provide a different indication and establishes a circuit to supply energy to said slow releasing relay provided said control relay is picked up, a circuit controlled by a front contact of said control relay governed by traffic conditions in said section, a slow releasing relay, a light signal for said section, said signal being of a type which has a member biased to a first position in which it conditions the signal to provide one indication and having a winding effective when energized to move said member to a second position in which it conditions the signal to provide a different indication and establishes a circuit to supply energy to said slow releasing relay provided said control relay is picked up, a circuit controlled by a front contact of said control relay for also supplying energy to the winding of said signal.

2. In combination, a section of railway track, a control relay governed by traffic conditions in said section, a slow releasing relay, a light signal for said section, said signal being of a type which has a member biased to a first position in which it conditions the signal to provide one indication and having a winding effective when energized to move said member to a second position in which it conditions the signal to provide a different indication and establishes a circuit to supply energy to said slow releasing relay provided said control relay is picked up, a circuit controlled by a front contact of said control relay for supplying energy to the winding of said signal, and a second circuit controlled by a front contact of said slow releasing relay and a back contact of said control relay for also supplying energy to the winding of said signal.

3. In combination, a section of railway track, a control relay governed by traffic conditions in said section, a slow releasing relay, a light signal for said section, said signal being of a type which has a member biased to a first position in which it conditions the signal to provide a first indication and having a winding effective when supplied with energy of reverse polarity to move said member to a second position in which it conditions the signal to provide a second indication and when supplied with energy of normal polarity to move said member to a third position in which it conditions the signal to provide a third indication and establishes a circuit to supply energy to said slow releasing relay provided said control relay is picked up, a circuit including back contacts of the control relay and of said slow releasing relay for supplying energy of reverse polarity to the winding of said signal, a circuit including a front contact of the control relay for supplying energy of normal polarity to the winding of said signal, and a circuit including a front contact of said slow releasing relay and a back contact of said control relay for also supplying energy of normal polarity to the winding of said signal.

4. In combination, a section of railway track, a control relay governed by traffic conditions in said section, a slow releasing relay, a light signal for said section, said signal being of a type which has a member biased to a first position in which it conditions the signal to provide a first indication and having a winding effective when supplied with energy of reverse polarity to move said member to a second position in which it conditions the signal to provide a second indication and when supplied with energy of normal polarity to move said member to a third position in which it conditions the signal to provide a third indication and establishes a circuit to supply energy to said slow releasing relay provided said control relay is picked up, a circuit including

5 back contacts of the control relay and of said slow releasing relay for supplying energy of reverse polarity to the winding of said signal, a circuit including a front contact of the control relay for supplying energy of normal polarity to the winding of said signal, and a circuit including a front contact of said slow releasing relay for also supplying energy of normal polarity to the winding of said signal.

10 5. In combination, a section of railway track, a first control relay governed by traffic conditions in said section, a second control relay governed by traffic conditions in advance of said section, a slow releasing relay, a light signal for said section, said signal being of a type which has a member biased to a first position in which it conditions the signal to provide a first indication and having a winding effective when supplied with energy of reverse polarity to move said member to a second position in which it conditions the signal to provide a second indication and when supplied with energy of normal polarity to move said member to a third position in which it conditions the signal to provide a third indication and establishes a circuit to supply energy to said slow releasing relay provided the second control relay is picked up, a circuit including a front contact of the first control relay and back contacts of the second control relay and of the slow releasing relay for supplying energy of reverse polarity to the winding of said signal, a circuit including front contacts of the first and second control relays for supplying energy of normal polarity to the winding of said signal, and a circuit including front contacts of the first control relay and the slow releasing relay for also supplying energy of normal polarity to the winding of said signal.

15 6. In combination, a section of railway track, a signal for said track section, said signal being of a type having a member biased to a first position in which it conditions the signal to provide a first indication, said signal having a winding effective when energized with current of reverse polarity to move said member to a second position in which it conditions the signal to provide a second indication and establishes a circuit to supply energy to a first repeater relay, said winding being effective when energized with current of normal polarity to move said member to a third position in which it conditions the signal to provide a third indication and establishes a circuit to supply energy to a second repeater relay, a first control relay governed by traffic conditions in said section and controlling the supply of energy to the winding of said signal, a second control relay governed by traffic conditions in advance of said section and controlling the polarity of the energy supplied to the winding of said signal in such manner that energy of reverse polarity is supplied to the signal winding when said relay is released and energy of normal polarity is supplied to the signal winding when said relay is picked up, a checking relay, a circuit for supplying energy to said checking relay when the first control relay is picked up provided the first repeater relay is also picked up and the second control relay and the second repeater relay are released, a circuit for also supplying energy to said checking relay when the first and second control relays are picked up provided the first repeater relay is released and the second repeater relay is picked up, and means including said checking relay for controlling traffic approaching said section.

7. In combination with a section of railway track, means governed by traffic conditions in advance of said section for at times supplying to the rails of said section coded energy of a first character and at other times of a second character, a code following track relay receiving energy over the rails of said section, a first and a second control relay associated with said track relay, means effective when the track relay is responding to energy of either character to energize the first control relay and effective only when the track relay is responding to energy of the second character to energize the second control relay, a signal for said section, said signal being of a type having a member biased to a first position in which it conditions the signal to provide a first indication and having a winding effective when energized with current of reverse polarity to move said member to a second position in which it conditions the signal to provide a second indication and to establish a circuit to supply energy to a first repeater relay and effective when energized with current of normal polarity to move said member to a third position in which it conditions the signal to provide a third indication and establishes a circuit to supply energy to a second repeater relay, a checking relay, a circuit including front contacts of the first control relay and the first repeater relay and back contacts of the second control relay and the second repeater relay for supplying energy to said checking relay, a circuit including front contacts of first and second control relays and of the second repeater relay and a back contact of the first repeater relay for also supplying energy to said checking relay, and means controlled by said checking relay for governing traffic approaching said section.

8. In combination with a section of railway track, means governed by traffic conditions in advance of said section for at times supplying to the rails of said section coded energy of a first character and at other times of a second character, a code following track relay receiving energy over the rails of said section, a first and a second control relay associated with said track relay, means effective when the track relay is responding to energy of either character to energize the first control relay and effective only when the track relay is responding to energy of the second character to energize the second control relay, a signal for said section, said signal being of a type having a member biased to a first position in which it conditions the signal to provide a first indication and having a winding effective when energized with current of reverse polarity to move said member to a second position in which it conditions the signal to provide a second indication and to establish a circuit to supply energy to a first repeater relay and effective when energized with current of normal polarity to move said member to a third position in which it conditions the signal to provide a third indication and establishes a circuit to supply energy to a second repeater relay, a checking relay, a circuit including front contacts of the first control relay and the first repeater relay and back contacts of the second control relay and the second repeater relay for supplying energy to said checking relay, a circuit including front contacts of first and second control relays and of the second repeater relay and a back contact of the first repeater relay for also supplying energy to said checking relay, said signal including a lamp, a lightout relay energized

in series with said lamp and having a contact included in series with each of the circuits for supplying energy to said checking relay, and means controlled by said checking relay for governing traffic approaching said section.

- 5 9. In combination with a section of railway track, means governed by traffic conditions in advance of said section for at times supplying to the rails of said section coded energy of a first character and at other times of a second character, a code following track relay receiving energy over the rails of said section, a first and a second control relay associated with said track relay, means effective when the track relay is responding to energy of either character to energize the first control relay and effective only when the track relay is responding to energy of the second character to energize the second control relay, a signal for said section, said signal being of a type having a member biased to a first position in which it conditions the signal to provide a first indication and having a winding effective when energized with current of reverse polarity to move said member to a second position in which it conditions the signal to provide a second indication and to establish a circuit to supply energy to a first repeater relay and effective when energized with current of normal polarity to move said member to a third position in which it conditions the signal to provide a third indication and establishes a circuit to supply energy to a second repeater relay, a checking relay, a circuit including front contacts of the first control relay and the first repeater relay and back contacts of the second control relay and the second repeater relay for supplying energy to said checking relay, a circuit including front contacts of first and second control relays and of the second repeater relay and a back contact of the first repeater relay for also supplying energy to said checking relay, a circuit including a back contact of the first control relay for supplying coded energy of the first character to the rails in the rear of said section, and a circuit including a front contact of the first control relay for supplying to the rails in the rear of said section coded energy of the first or second character according as said checking relay is released or picked up respectively.
- 10 50 10. In combination, a section of railway track, a first and a second control relay, means governed by traffic conditions in said section and in advance of said section for at times supplying energy to said first control relay and at other times supplying energy to said second control relay, a slow releasing relay, a signal for said section having an upper and a lower unit, each of said signal units being of a type having a movable member biased to a first position in which it conditions the unit to provide one aspect and having a winding effective when energized to move said member to a second position in which it conditions said unit to provide a second aspect, a circuit including a front contact of said first control relay for supplying energy to the winding of said upper signal unit, and a circuit including a front contact of said first control relay and a contact of said upper signal unit closed only when the movable member of said signal unit is in its second position for supplying energy to said slow releasing relay, said slow releasing relay being effective when picked up to establish a circuit to also supply energy to the winding of said upper signal unit, said second control relay being effective when energized to establish a
- 15 60 65 70 75

circuit to supply energy to the winding of the lower signal unit, said slow releasing relay having a release time longer than the pick-up time of the second control relay, whereby on a change in traffic conditions which results in deenergization of the first control relay and energization of the second control relay the slow releasing relay maintains the supply of energy to the winding of the upper signal unit until the second control relay becomes energized.

11. In combination, a section of railway track, a first and a second control relay, means governed by traffic conditions in said section and in advance of said section for at times supplying energy to the first control relay and at other times supplying energy to the second control relay, a signal for said section having an upper and a lower unit, each of said signal units being of a type which has a member biased to a first position in which it conditions the signal unit to provide one aspect and having a winding effective when energized to move said member to a second position in which it conditions the signal unit to provide a second aspect, a first and a second slow releasing relay, a circuit including a front contact of the first control relay for supplying energy to the winding of said upper signal unit, a circuit including a front contact of said first control relay and a contact of said upper signal unit closed only when the movable member of said unit is in its second position for supplying energy to the first slow releasing relay, a circuit including front contacts of said first slow releasing relay for also supplying energy to the winding of said upper signal unit, a circuit including a front contact of said second signal control relay for supplying energy to the winding of said lower signal unit, a circuit including a front contact of said second signal control relay and a contact of said lower signal unit closed only when the movable member of said unit is in its second position for supplying energy to said second slow releasing relay, and a circuit including a front contact of said second slow releasing relay for also supplying energy to the winding of said lower signal unit.

12. In combination with a section of railway track, a control relay governed by traffic conditions in said section, a slow releasing relay, a light signal for said section, said signal having a member biased to a first position in which it conditions the signal to display one indication and having an operating winding effective when energized to move said member to a second position in which it conditions the signal to display a different indication and establishes a circuit for supplying energy to said slow releasing relay provided said control relay is picked up, a circuit

controlled by a front contact of said control relay for supplying energy to said operating winding, a second circuit controlled by a front contact of said slow releasing relay for also supplying energy to said operating winding, and means controlled by said slow releasing relay for governing traffic approaching said section.

13. In combination with a section of railway track, a signal for said section having an upper and a lower unit each having a lamp, each of said units having a member biased to a first position in which it conditions the associated unit to display a first indication, each unit having an operating winding effective when energized with current of one polarity to move said member to a second position in which it conditions the unit to display a second indication and effective when energized with current of the other polarity to move said member to a third position in which it conditions the unit to display a third indication, means governed by traffic conditions for at times supplying energy of said one polarity and for at other times supplying energy of said other polarity to the winding of said upper unit and for at both said times supplying energy to the winding of said lower unit, a lightout relay for checking the integrity of the lamp of one of said units, and means controlled by said lightout relay effective when a defect occurs in the associated lamp for preventing the supply of energy of said other polarity to the other unit.

14. In combination with a section of railway track, a signal for said section having an upper and a lower unit each having a lamp, each of said units having a member biased to a first position in which it conditions the associated unit to display a first indication, each unit having an operating winding effective when energized with current of one polarity to move said member to a second position in which it conditions the unit to display a second indication and effective when energized with current of the other polarity to move said member to a third position in which it conditions the unit to display a third indication, means governed by traffic conditions for at times supplying energy of said one polarity and for at other times supplying energy of said other polarity to the winding of said upper unit and for at both said times supplying energy to the winding of said lower unit, a lightout relay for checking the integrity of the lamp of said upper unit, and means controlled by said lightout relay effective when a defect occurs in the associated lamp for preventing the supply of energy of said other polarity to the lower unit to thereby prevent the display of a proceed indication by said lower unit.

RALPH R. KEMMERER.
